UNITED STATES PATENT OFFICE.

WARREN W. SIMPSON, OF INDIANAPOLIS, INDIANA, ASSIGNOR TO LA FAYETTE MOTORS COMPANY, A CORPORATION OF DELAWARE.

DESIGN FOR A RADIATOR-SHELL FOR MOTOR-VEHICLES.

55,822.

Specification for Design.

Patented July 13, 1920.

Application filed January 10, 1920. Serial No. 350,707. Term of patent 14 years.

To all whom it may concern:

Be it known that I, WARREN W. SIMPSON, a citizen of the United States of America, residing in the city of Indianapolis, county of Marion, and State of Indiana, have invented a new and original and ornamental Design for a Radiator-Shell for Motor-Vehicles, of which the following is a specification, reference being had to the accompanying drawings, forming a part thereof.

In the drawings Figure 1 is a front elevation of the radiator, showing my new design. Fig. 2 is a side elevation.

I claim:

The ornamental design for a radiator shell for motor vehicles, as shown.

WARREN W. SIMPSON.
